UNITED STATES PATENT OFFICE.

DORA E. EILAR, OF BORGER, TEXAS, ASSIGNOR TO JOHN E. WELTON, OF BOWLING GREEN, OHIO.

SNUFFER.

Application filed January 21, 1927. Serial No. 162,552.

By way of explanation, it may be stated that gas frequently escapes from an oil well or other well, when the top of the casing head is opened, the result being that operators often are asphyxiated. The foregoing being understood, it may be stated that the object of this invention is to provide novel means whereby a casing head may be opened at the top, and, at the same time, a dangerous outflow of gas will be prevented.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in longitudinal section, a device constructed in accordance with the invention;

Figure 2 is a top plan;

Figure 3 is a vertical section taken on the line 3—3 of Figure 2;

Figure 4 is a sectional view showing a modification.

The numeral 1 marks, generally, a casing head for a well, the head 1 including a tubular body 2 having a top 3 and a frusto conical bottom 4, the bottom 4 having a nipple 5 which is internally threaded as at 6, or constructed otherwise, so that the well casing may be attached thereto. The top 3 of the casing head is supplied with an opening that may be in the form of a tubular member 7 mounted intermediate its ends in the top 3, the tubular member 7 being threaded at 8, or constructed otherwise, so that a closure (not shown) may be assembled therewith. The body 2 of the casing head 1 is provided near to its upper end with lateral outlets 9, through which the product of the well flows.

At this point, the description of the invention profitably may be suspended, in order to make manifest the particular problem with which this invention proposes to deal.

When the tubular member 7 is opened, as shown in the drawings, in order to permit op-

erators to work in the well, poisonous gases, existing as a by-product of the well, or otherwise, often rush out, upwardly, through the member 7, the operators of the well being prostrated or even killed, in some instances.

The structure hereinafter described operates in such a way that, even though the tubular member 7 may be opened at its upper end, as shown in the drawings, no gases will flow therethrough. Having that desirable result in mind, I provide the body 2, near to its upper end, with inlets 10, of which there may be any desired number. By way of the inlets 10, steam, air, gas, or any other fluid under pressure may be introduced into the casing head 1. A conical apron 11 connects the lower end of the tubular member 7 with the top 3 of the body 2. A conical wall 12 is located below the apron 11 and is spaced vertically therefrom, the upper edge of the wall 12 being connected to the tubular body 2, below the inlets 10, as shown in Figure 1, and above the outlets 9, as shown in Figure 3. The conical wall 12 has an aperture 25, about which is located a depending tubular extension 14. The space between the wall 12 and the apron 11 constitutes a chamber 15, and it is into this chamber that fluid pressure, derived from the inlets 10 is discharged, the fluid under pressure passing downwardly through the chamber 15 and into or through the tubular extension 14. There is an inverted conical baffle 16 on the lower end of the extension 14, and other baffles 17 are located below the baffle 16, in spaced relation to each other, the baffles 16 and 17 being connected together, and to the bottom 4, in any suitable way, for instance by means of rods 18. All of the baffles 16 and 17 have openings 28 which are aligned with the extension 14 and with the tubular member 7, so that a person can work downwardly through the parts 7, 14, 16, 17 and 5, into the well casing.

In practical operation, the gas rising in the well is received within the body 2 and is carried laterally, to some extent, by the baffles 17 and 16. In order, however, to prevent the gas from flowing upwardly through the parts 14 and 7, the pressure is increased in the inlets 10, the chamber 15, and in the extension 14, so as to off-set and back up the gas, the gas thereby being prevented from flowing upwardly through the extension 14 and the member 7. The gas, thus, is constrained to move upwardly beneath the wall 12 and out-

wardly through the outlets 9. The pressure of the gas that rises, as a by-product or otherwise, within the well, varies from time to time and, therefore, in practice, sufficient pressure is delivered through the inlets 10 to overcome the pressure of gas in the well, and, generally, the pressure delivered at 10 into the casing not merely establishes equilibrium with respect to the gas pressure in 15 the well, but, really, overcomes that pressure, the steam, air, gas, or other fluid under pressure flowing downwardly through the extension 14 and away through the outlets 10, with the gas.

15 In Figure 4 the flow line pipe is marked by the numeral 19 and into it extends a pipe 20, held in place by nuts 24, the pipe 20 having a rectangularly disposed arm 21 carrying a nozzle 22 within which is located a 20 spreader 23. This instrumentality may be used when it is desired to speed up the flow of gas or oil, by steam or other fluid under pressure, before the gas or oil enters the body 2 by way of the nipple 5.

25 What is claimed is:—

1. A casing head having an opening in its top, and provided with an outlet, there being a wall in the casing and separating the opening from the outlet, the wall having an aperture alined with the opening, and means for admitting fluid-pressure to the casing, upon 30

the same side of the wall as the opening, to prevent gas from passing upwardly through the aperture and the opening.

2. A casing head provided in its top with 35 an inwardly extended tubular member and provided with a transverse wall having a tubular extension alined with the tubular member, the casing being provided with an outlet located on one side of the wall, and 40 with a fluid-pressure inlet located on the opposite side of the wall and discharging about the tubular member.

3. A casing head having an opening in its 45 top and provided with an outlet, there being a wall in the casing and separating the opening from the outlet, and a plurality of baffles in the casing below the wall, the wall and the baffles having apertures alined with the 50 opening.

4. The combination with a casing head having a tubular member in its top, and having a lateral outlet, of an inclined fluid-pressure pipe discharging into the tubular member at an acute angle to the axis thereof, the tubular member being provided intermediate 55 its ends with a nozzle discharging into the outlet.

In testimony that I claim the foregoing as my own, I have hereto affixed my signature.

DORA E. EILAR.
